CLAIM

The ornamental design for an ash sifting shovel, as shown and described.

DESCRIPTION

FIG. 1 is a front view of an ash sifting shovel showing my new design;

FIG. 2 is a rear view of the ash sifting shovel;

FIG. 3 is a left side view of the ash sifting shovel, a right side view being a mirror image thereof;

FIG. 4 is a top view of the ash sifting shovel;

FIG. 5 is a bottom view of the ash sifting shovel; and,

FIG. 6 is a cross-sectional view of the ash sifting shovel taken along line 6-6 of FIG. 1.
